UNITED STATES PATENT OFFICE.

WILLIAM R. GARNER, OF GALVESTON, TEXAS, ASSIGNOR TO LYtle J. HUNTER, OF COVINGTON, KENTUCKY.

STATION-INDICATOR.

SPECIFICATION forming part of Letters Patent No. 593,976, dated November 16, 1897.

Application filed November 11, 1896. Serial No. 611,698. (No model.)

To all whom it may concern:

Be it known that I, WILLIAM R. GARNER, a citizen of the United States, and a resident of the city of Galveston, in the county of Galveston and State of Texas, have invented certain new and useful Improvements in Automatic Station-Indicators, of which the following is a specification.

The several features of my invention and the various advantages resulting from their use conjointly or otherwise will be apparent from the following description and claims.

In the accompanying drawings, making part of this specification, and in which similar letters of reference indicate corresponding parts, Figure 1 is a front elevation of a machine illustrating my invention. Fig. 2 is a rear view of the said invention when the back of the chamber has been removed. Fig. 3 is an end elevation, enlarged, of that end of the chamber which is at the right hand in Fig. 2, and showing both of the sprocket-wheels in engagement with the sprocket indicator-chain. Fig. 4 is a vertical transverse section of the device, taken in the plane of the dotted line 4 4 of Figs. 1 and 2, that face of the section being shown which faces toward the right in Fig. 2 and toward the left in Fig. 1. Fig. 5 is a view in perspective of the sprocket-wheel, ratchet-wheel, and pawl, located at the right-hand end of the box or chamber in Fig. 2.

A indicates the box or chamber, having the roof B, front side B², rear side B³, and bottom B⁴ and provided with ends C C. The front of the chamber is open, except as closed by the movable curtain or display-strip D. This display-strip fills the entire front or substantially the entire front of the chamber and moves in connection with the following rollers. E is a large positive roller journaled in the lower rear part of the chamber and having the shaft E², by which it is actuated, projecting through the adjacent side C of the chamber and fixed to a ratchet-wheel F and to a sprocket-wheel G. The ratchet-wheel is provided with a pawl F², pivoted at F³ to the end of the chamber. Its function is to prevent the roller from moving in a reverse backward direction until intentionally lifted by human agency. One end of the display-

strip D is fastened on the roller E and is continued forward and around an idler H, thence up in front of the open portion of the compartment, in which space it is displayed to view, and at the upper front corner of the chamber passes around another idler-roller I, and thence passes rearward and around a spring-roller J. This spring-roller J is preferably made upon a plan of construction similar to that used in the ordinary spring-roller curtains now in use; but any suitable mode of causing it to revolve strongly in a given direction, so as to roll up the strip D upon it as fast as permitted and to elastically resist the unrolling of the strip D from it, may be employed.

The sprocket-strap K engages with the sprocket-wheel G and also with another sprocket-wheel H, fixed at some suitable point within reach of the motorman or conductor or other person operating the station-indicator, as the case may be. This strap K (a small portion of which is shown enlarged in Fig. 2 below that portion of it which is attached to the sprocket-wheel G in Fig. 2) has marked upon it at proper intervals the names of the stations in their proper order of sequence and corresponding in number and identity to those marked in large letters upon the strip D.

The mode in which this apparatus operates is as follows: At the beginning of the trip all of the curtain or display-strip is unwound off the roller E and wound up on roller J, with the exception, of course, of the portion that is stretched from roller E around the idler-rollers H I to the spring-roller J. If the proper name is displayed upon the display-strip for starting, the operator waits until the next station is reached before operating the machine; otherwise he immediately turns the sprocket-wheel H so as to bring the proper name for the station next to be reached into view in the compartment. He is enabled to do this without looking at what is displayed from the chamber or compartment by means of the indicating-names upon the sprocket-wheel strap. As the necessity arises for the notification of the station about to be reached the operator moves the sprocket-chain H so as to bring this name of the strap to a given

point, and the corresponding name will be found displayed upon the indicating-strip D. This operation rolls the strip D gradually upon the roller E, and the strip is prevented from being drawn back through the agency of the pawl F², engaging the ratchet F and allowing the strip to be rolled upon the roller E, but not to be unwound therefrom. The strip D will not go backward and will therefore gradually display the indicating-names desired, the spring-roller J in the meantime keeping the strip D taut. When all the stations have been successively reached, the operator raises the pawl F² and allows the spring-roller to act, whereupon the latter rolls the strip D upon itself and unwinds correspondingly from the roller E, thereby placing the strip in a position ready for another trip of the car over the same tracks in the same direction.

This station-indicator may be used at night as well as by day, and in order to render the stations marked on the strip conspicuous at night lights L are used, and these lights are preferably electric ones, and preferably incandescent lights. It will be understood that the sprocket display-strip is to be carried to any part of the car desired, while, on the other hand, the compartment A will be located on the top of the car or in a conspicuous place on the car, and this conspicuous place will frequently be altogether out of reach of the operator.

My invention is simple of construction, durable, quite economical of cost, and very efficacious in action and result. Its advantages are quite obvious.

What I claim as new and of my invention, and desire to secure by Letters Patent, is—

1. In a machine for indicating stations, the combination of the spring-roller J, display-strip D containing names of the stations successively marked thereon, roller E having shaft E² connected to a wheel positively operated by a pulley-band on which are marks

or characters whereby the stations to be displayed by the strip D are marked, substantially as and for the purposes specified.

2. In a station-indicator, the combination of the spring-roller J, idler-rollers and roller E, strip D connected to rollers J and E and made taut upon the idler-rollers, the roller having shaft E², engaging pawl F² fixed to the frame of the machine, and the wheels G fixed on the same shaft for positively operating the roller E, in combination with means whereby the rotation of the wheel G is in accordance with indicating-marks adjacent to and at the inspection of the operator, substantially as and for the purposes specified.

3. In an indicating-machine, the combination of the compartment, spring-roller J, roller E, strip D duly strained and arranged to move across the front of the chamber, and shaft E² of the roller, ratchet-wheel F and sprocket-wheel G mounted on said shaft, pawl F² of the frame engaging the ratchet-wheel F, sprocket-wheel strap K having stations marked thereon corresponding to the indications as marked on the indicating-strip D and the sprocket-wheel H combined with the endless strap K, substantially as and for the purposes specified.

4. The combination of the lantern box or case, rectangular at bottom, and at its front upper corner, and the positively-operating roller E at the rear lower corner, idlers H and I at the respective front corners, and the spring-roller J, at the upper part of the case in rear of idler H, and a display flexible sign or curtain stretched between rollers E and J, and in front of and on idlers H and I, and the lamps located in the space between the rolls E and H, and I and J, substantially as and for the purposes specified.

WILLIAM R. GARNER.
